UNITED STATES PATENT OFFICE

HERBERT R. STRATFORD, OF CLEVELAND, OHIO, ASSIGNOR TO THE STRATMORE COMPANY, OF CLEVELAND, OHIO, A CORPORATION OF OHIO

METHOD OF SURFACING

Application filed January 15, 1926, Serial No. 81,565. Renewed August 26, 1930.

The present invention, relating as indicated, to methods of and apparatus for surfacing, is particularly directed to an improved method and apparatus for bringing to a perfectly smooth and highly polished condition such surfaces as those produced by spraying lacquer and similar materials onto metal or other surfaces, as for example, in automobile bodies. Lacquer is today sprayed onto metal automobile bodies which have first been coated with one or more priming coats by means of an air spray, and as lacquer dries very rapidly, the appearance of this sprayed surface is extremely irregular and has what is called an "orange peel" surface. The various portions of this surface lie at different angles to each other and therefore do not reflect light in the same directions, and as a consequence do not give a highly reflective surface, and have relatively no gloss. The lacquer is extremely tough and durable and can be brought to a smooth condition by methods heretofore used only after the application of a great amount of time and laborious effort.

The present invention relates to an improved method and apparatus for bringing such surfaces to the same highly reflective or glossy surface that has heretofore been obtainable only by extremely expensive methods when applied to lacquer or by other types of surfacing such as varnish and the like. To the accomplishment of the foregoing and related ends, said invention, then, consists of the means hereinafter fully described and particularly pointed out in the claims.

The annexed drawing and the following description set forth in detail certain means and one mode of carrying out the invention, such disclosed means and mode illustrating however, but one of the various ways in which the principle of the invention may be used.

In said annexed drawing:-

Fig. 1 is a side elevation showing my improved apparatus operative upon the surface; Fig. 2 is a vertical section through my apparatus; Fig. 3 is a longitudinal section of a metal sheet covered with lacquer as first applied by spraying; Fig. 4 is a similar view but showing the same surface after it has been brought to a perfectly smooth and highly reflective condition by my improved method and Fig. 5 is a fragmentary view on an enlarged scale illustrating certain details in the construction of the apparatus.

My improved method consists briefly stated, in first grinding down to a smooth condition the irregular surface which is left after spraying lacquer onto a coated metal surface by moving across the surface a flexibly supported rubbing element, preferably in the form of a disc, at relatively high speed with which element either is provided with abrasive means for cutting down the irregularities on the surface or is operated in conjunction with abrasive material which is applied to the body in the form of a paste, while at the same time applying liquid to the surface being operated upon in such a way as to necessarily flush the abraded material from between the surface element and the surface being operated upon. In Figs. 1 and 2 I have shown an apparatus capable of carrying out my improved method and it will be understood that this apparatus is merely illustrative of mechanism for this purpose and the particular mechanism described and herein shown exemplifies merely the best form of apparatus which I have found for the present purpose. In Fig. 1 I have shown an article 1 which may represent a metal panel of an automobile body for example, which is provided with one or more priming coats and a coat of lacquer sprayed onto the final priming coat. My apparatus consists of a casing 2 provided with handles 3 and 4, through one of which

there ends a flexible driving shaft 5 driving through beveled gears 6 and 7 (Fig. 2), a shaft 8 extending downwardly from the semispherical casing 2 and carried on its lower end is a flexible yielding support or pad 9 against which is disposed the surfacing element 10 which is removably secured to the end of the shaft 8. The surfacing element may consist either of an abrasive disc 10 or a rubbing element such for example as a felt disc or the like in which abrasive material is impregnated or to which it is supplied for the operation while the supporting pad 9 may take various forms and may consist of one or more relatively thin metal discs 11 and 12 such as I have here shown. Liquid is supplied through a conduit 13 to the interior of the casing 2 and is then passed down through an opening in the shaft 20 8 and discharged laterally through a port 14 at the end of the shaft into a registering port 15 formed in the removable head member 16 which secures the surfacing element in place against the resilient support. In this way, liquid is continuously supplied to the center of the surfacing element and is directed through the lateral ports toward that portion of the pad which is normally pressed against the work, that is, the portion opposite the sector of the machine embraced between the two handles 3 and 4. This apparatus may be applied to the surface in the manner illustrated in Fig. 1, that is, an operator may grasp the two handles 3 and 30 4 and force the segment of the surfacing disc opposite the handles against the surface which is to be worked upon, in this way flexing the disc and support and applying the surfacing element with considerable pressure which is however substantially uniform against the surface. The surfacing disc is rotated at a relatively high rate of speed which should be from one thousand to fifteen hundred surface feet a minute while a sufficient quantity of liquid should be supplied to remove the material abraded from the surface as rapidly as formed. The liquid is supplied to the surface in such a way that the tendency of the rotating disc is to carry 40 the water across the surface of the work operated upon and then by the action of centrifugal force throw the water and the material in suspension therein off from the work at considerable speed.

Following the rubbing down of the under coat surface, one or more finishing coats are applied, usually by spraying the material onto the surface which produces, as already stated, a rough irregular surface. This surface is then brought to a smooth and highly reflective condition by abrading it at relatively high speed with material containing abrasive, usually in the form of a paste and a surfacing element which may take the form of the flexibly supported felt pad which

is shown in my copending application, Serial No. 24,972, filed April 22, 1925. The abrasive material is usually first applied to the body and is then rubbed with the felt pad until the abrasive in the material has brought the irregular surface to a relatively smooth condition while at the same time most of the paste has been thrown off, dried or absorbed in the pad, from the body by the centrifugal force of the felt rubbing disc, 75 which is of course rotated at a relatively high speed or has been picked up and held by the surface of this disc.

The next step in the operation of finishing the surface is to polish the fairly smooth surface produced in the manner described above which may be done by rubbing the surface with a felt pad of the character already described, at a relatively high rate of speed. The action of this felt is to remove and absorb 80 any paste or abrasive or foreign material which remains on the surface and to at the same time smooth or flow the lacquer of the final coat into a uniform and smooth surface without irregularities and without any 85 scratches or other marks which will be detrimental to the reflective action of this surface.

It will be readily understood that it may be possible to combine these last two steps, that is, the rubbing and the polishing steps, under certain conditions where, for example, the surface to be polished is practically smooth and has but few irregularities in which case a long continued polishing action 90 may be sufficient to both bring the surface to a level condition and also produce a high gloss but in most cases, I find it desirable to employ two separate operations of the character already described.

In Figs. 3 and 4 there is shown a panel, which may be either of wood or metal, 20, on which has been sprayed a coating composition, such for example as varnish, lacquer or the like, which as first deposited, particularly in the case of lacquer, has what is termed an orange-peel surface consisting of a series of projecting portions 22, the layer itself being designated as 21. Because of this irregular roughened surface there is no brilliancy or luster to such coating as first applied and it must be smoothed and leveled by some means or method such as that which I have just described. By my improved method this coating is brought to a smooth level 100 condition, indicated at 23 in Fig. 4, and when so conditioned is brilliant and reflective and possesses what is termed a high luster.

Other modes of applying the principle of my invention may be employed instead of 105 the one explained, change being made as regards the means and the steps herein disclosed, provided those stated by any of the following claims or their equivalent be employed.

I therefore particularly point out and distinctly claim as my invention:—

1. In a method of polishing lacquer, the steps which consist in moving a pad over a lacquer coated surface at high speed to first smooth by actually flowing the lacquer by the generated heat and then polish the coating thereon to a high lustre.

2. In a method of polishing lacquer, the steps which consist in moving a flexibly supported disc over a lacquer coated surface at high speed to generate sufficient heat to first smooth by flowing the lacquer and then polish the coating thereon to a high luster.

15 Signed by me, this 24th day of December, 1925.

HERBERT R. STRATFORD.
